MATERIAL HANDLING DEVICE

Milton P. Whitmore, Tampa, and Lucio Maddalena, Orlando, Fla., assignors to Clark Equipment Company, Buchanan, Mich., a corporation of Michigan
Filed Jan. 22, 1960, Ser. No. 4,146
9 Claims. (Cl. 214—307)

This invention relates to material handling devices and is more particularly concerned with a type of receptacle used in the citrus industry, which is adapted to be mounted and conveyed by a fork lift type truck.

While the basic inventive concept is by no means limited to this type of conveyance, that form of the invention herein set forth by way of illustration, is specifically adapted to such equipment. It will, of course, be understood that the vehicle forms no part of the present invention and that the device herein set forth may be mounted on and operated by a wide variety of such devices and that it may be readily adapted, by those skilled in the art, to vehicles of an entirely different nature.

In carrying out our invention in one form, we provide a supporting structure adapted to be mounted on a fork lift truck or the like. The supporting structure cooperates with a rod to support a container which has its bottom pivotally attached thereto by means of the rod. The supporting structure also includes means for actuating the bottom between open and closed positions.

It is among the objects of the present invention to provide a novel, simple and improved self unloading material handling device in which the bottom may be readily and easily opened to permit discharge of material. It is a further object to provide a material handling device of the type set forth in which the bottom may be opened for discharge of material as an incident to a vertical movement of the normal supporting structure for the receptacle. More specifically, it is an object of the present invention to provide a material handling device for a fork lift vehicle which is particularly adapted for use in the citrus industry. Numerous other objects, features and advantages of the present invention will be apparent from a consideration of the following specification taken in conjunction with the accompanying drawing in which:

FIGURE 1 is a perspective view of one form of the invention as applied to a conventional fork lift type truck,

FIGURE 2 is a perspective view of the supporting means for the receptacle,

FIGURE 3 is a side elevation of the supporting structure showing the support of the receptacle with the bottom in closed position, and

FIGURE 4 is a view similar to FIGURE 3 showing the bottom open for discharge of material from the receptacle.

In that form of the invention here set forth, the device, generally indicated by the numeral 10, is adapted to be supported and elevated by a fork lift type of vehicle generally indicated by the numeral 11.

It will, of course, be understood that the invention is not concerned with structural details or arrangement for power mechanism of the lift truck here indicated. Therefore, no specific discussion of the mechanism herein shown by way of illustration is believed appropriate. Such generally conventional material handling equipment, regardless of make and whether or not the lift mechanism is mechanically, hydraulically or electrically powered, may be characterized as including upright standards here identified by the numerals 12, between which, lifting mechanism including chains 13, provide for the elevation or lowering, by power mechanism, of mounting members 14. Such members are of a wide variety and type, variously designed to suit various material handling

2

problems, as for instance, to support forks, clamps, cranes, receptacles and the like. In the present instance, a similar pair of vertically spaced parallel mounting base members 14 are illustrated.

5 The apparatus of the present invention includes a face plate 15 upon the upper edge of which is mounted a pair of longitudinally spaced hooks 16. Hooks 16 serve to secure plate 15 to upper member 14 through a rabbeted construction indicated at 17. At each end of the generally rectangular plate 15, a forwardly extending plate 18 is secured. Each plate 18 has a configuration, as shown, including recess 19 in the upper edge thereof for a reason explained hereinafter. A generally downwardly extending tilt bar link 20 is pivotally connected at its upper end to the inner face of each support plate 18 as at 20'. At its lower end each link 20 is formed with a bearing connection 21 engaging one end of a transverse tilt bar 22 thereby forming a transverse U-shaped tilt assembly pivotal about the upper ends of links 20. A toggle 26 comprising a pair of pivotally connected links is pivotally connected at one end to the inner face of each support plate 18 as at 28, and at the other end to the one end of tilt bar 22 as at 27. A double-acting fluid actuator 24 is pivotally connected to the inner face of each support plate 18 at 23. The piston rod 25 of each actuator 24 is pivotally connected to respective ones of toggle 26 at the pivotal connection of the links of each toggle. The fluid actuator and toggle assembly serves to actuate the U-shaped tilt assembly 20, 22 between forwardly and 30 rearwardly disposed positions for a purpose which will be explained shortly.

A pair of forwardly and downwardly extending truncated parallel brackets 30 are secured to base plate 15 intermediate support plates 18. Secured to the outer 35 ends of the brackets 30 is a transverse bearing plate 31 which preferably is located a substantial distance beneath and slightly rearwardly of recesses 19.

40 A receptacle or container 35 is adapted to be supported by support plates 18 and bearing plate 31 of the above-described support assembly in a plane substantially parallel to the truck supporting surface. The container preferably comprises a rectangular arrangement of four sidewalls 32 of frame and wire mesh construction and a bottom 36 pivotally connected to side walls 32. It will be appreciated that configurations other than rectangular could be utilized, and also that the sidewall construction could be of solid construction, for example, rather than of frame and wire mesh construction.

45 The container 35 has a rod 33 which extends transversely of the container and beyond the sidewalls adjacent the upper rear edge portion thereof. The projecting portions of rod 33 are adapted to be received by recesses 19 in support plates 18 for supporting container 35 for elevation in the upright 12 while bearing plate 31 is adapted to bear against the rear wall of the container and serves to support the container against downward rotative movement and to maintain same horizontal. It will be understood, of course, that any suitable projecting elements could be secured to the side walls of the container in substitution of rod 33.

50 The bottom assembly 36 of the container comprises a rectangular closure plate having a transverse dimension which is preferably somewhat larger than the corresponding dimension between the sidewalls of the container and somewhat smaller than the distance between support plates 18. A pair of upwardly extending triangular side plates 34 are secured to opposite ends of the closure plate and are pivotally connected to and supported by the projecting portions of rod 33 in the apex portions thereof and intermediate the container sidewalls and the support plates 18. It will be appreciated that the projecting ends

of rod 33 include both a support portion which is received in recesses 19 for supporting the entire container 35 and a bearing portion upon which the side plates 34 are pivoted.

The operation of our invention will now be described. Assume that container 35 is resting upon the ground in a citrus orchard and is loaded with citrus fruit. In order to transport the loaded container to another location, a lift truck having the support assembly mounted thereon is maneuvered into position and picks up the loaded container by engaging the projecting outer portions of rod 33 in recesses 19 whereupon the hoist mechanism 12, 13, 14 is elevated. In order to prevent bottom assembly 36 from opening, the U-shaped tilt assembly 20, 22 is held in a forwardly disposed position in abutment with the rear edges of side plates 34 by the hydraulic actuators and toggles 24 and 26 located as shown in FIGURE 3. The loaded container may be deposited at a new location merely by reversing the pick-up operation. If it is desired to unload the container at the new location, then it is held at a desired elevation and the bottom 36 is opened by retracting at a desired rate the actuator and toggle assembly 24, 26 which permits the U-shaped tilt assembly 20, 22 to move to its rearwardly disposed position whereby the weight of the bottom closure assembly 36, as well as the weight of the load, causes the closure assembly to pivot about rod 33 at the desired rate provided by rearward movement of rod 22. The rate of load discharge is controlled both by the rate of actuator movement and by the extent of retraction thereof which may be controlled by the operator. During dumping operations container portion 32 continues to be disposed as shown in FIGURE 4 while the side plates 34 are retracted intermediate the sidewalls 32 and support plates 18 since the bottom assembly embodies no rear wall and intermediate support 31 will not interfere with said action. Extension of the actuators 24 will return the links of toggles 26 to coaxial position moving bar 22 forwardly to close the bottom closure assembly.

Heretofore mechanization of citrus fruit handling has not met with much success because the fruit must be handled with care in order to avoid bruising it. The present invention provides a relatively simple and low-cost device which is capable of handling citrus fruit and other such easily damaged goods with minimum bruising.

Further, our device is well adapted to economical operation. For example, a number of containers 35 can be located in an orchard at intermediate collection points to be filled by the pickers and serviced by a single lift truck having the support assembly attached thereto. The loaded containers can be transported to a central collection point by the lift truck where they can be stored, or unloaded and returned to the intermediate collection point. Loaded containers can also be deposited directly onto a flatbed truck or other vehicle for transport to a distant location wherein another lift truck utilizing the present invention unloads the containers from the vehicle and then either store the same or dump the contents at any desired place.

It will, of course, be understood that the invention is here shown in one of its many commercially feasible embodiments but that in the practice of the invention, numerous changes, modifications and the full use of equivalents may be resorted to without departure from the spirit or scope of the invention as outlined in the appended claims.

What we claim is:

1. A material handling device of the character set forth including a receptacle having side walls, a bottom closure, means extending from adjacent the upper edges of said side walls to provide lifting means for said receptacle and side members extending upwardly from said closure pivotally engaging said lifting means, and means for controlling the pivotal movement of said side members and hence said bottom closure.

2. In a material handling device a receptacle having a

closed wall structure, a top and bottom opening defining edges of said wall structure, a bottom closure pivotally mounted from said wall structure for opening and closing the bottom opening thereof and a common receptacle support and bottom closure mounting means mounted on said wall structure, releasable means for restraining said bottom closure against pivotal movement away from said bottom edges, and means for supporting said receptacle from said common support and mounting means and preventing pivotal movement in one direction of said wall structure about said mounting means.

3. A material handling device for use with lift trucks comprising a bottom unloading receptacle having receptacle forming walls, means secured to said walls engageable with lift mechanism of a lift truck for raising and lowering said receptacle, a bottom closure for said receptacle and means secured to said walls mounting said bottom closure for pivotal opening and closing movement and located closely adjacent said engageable means, means operatively connected to the lift mechanism of the lift truck for preventing tilting movement of said receptacle in at least one direction, and means movable with the lift mechanism of the lift truck for controlling the pivotal movements of said bottom closure.

4. A material handling device for use with lift trucks comprising a bottom unloading receptacle having receptacle forming walls open at the top and bottom, pivoted closure means for opening and closing the bottom opening and means mounted on said walls having a first portion for supporting said receptacle from lift mechanism of a lift truck and a second portion mounting said pivoted closure, means for preventing tilting of said receptacle in at least one direction when said bottom opening is open, and means movable with the lift mechanism of the lift truck for controlling the pivotal movements of said bottom closure.

5. A material handling device for use with lift trucks comprising a bottom unloading receptacle having receptacle forming walls open at the top and bottom, pivoted closure means for opening and closing the bottom opening and means secured adjacent the upper edge of said walls having a first portion for supporting said receptacle from lift mechanism of a lift truck and a second portion mounting said pivoted closure, means cooperating with said first portion to prevent pivotal movement of said receptacle about said first portion, and means movable with the lift mechanism of the lift truck for controlling the pivotal movements of said bottom closure.

6. A material handling device for use with lift trucks comprising a bottom unloading receptacle having receptacle forming walls open at the top and bottom, pivoted closure means for opening and closing the bottom opening and means secured adjacent the upper edge of said walls having a first portion for supporting said receptacle from lift mechanism of a lift truck and a second portion mounting said pivoted closure, means for maintaining said receptacle in a fixed position during opening movement of the closure means, and means movable with the lift mechanism of the lift truck for controlling the pivotal movements of said bottom closure, said movable means including remotely controlled hydraulic cylinders operable independently of movements of the lift mechanism.

7. For use in a fork lift truck, a material handling device comprising a receptacle having a plurality of side walls, transversely protruding means adjacent the upper edges of two opposite sides constituting receptacle lifting means, a lifting member carried by the lift mechanism of the truck, arms extending from said lifting member engageable with said lifting means to raise and lower said receptacle, a bottom closure for said receptacle, side members extending from said bottom closure to said lifting means, pivotal mountings for said side members engaging said lifting means, movable means supported from said lifting member engageable with said side members for restraining pivotal movement of said side members, and means supported from said lifting member and engaging

said receptacle below said pivotal mountings for precluding tilting movement of said receptacle when said closure is pivoted upon pivotal movement of said side members.

8. For use with a vehicle, a material handling device comprising a support assembly adapted to be attached to the vehicle, a container, a bottom for said container pivotal between open and closed positions, means pivotally connecting said bottom to said container, means for supporting said container from said support assembly, said connecting means and said pivot means comprising a common member, intermediate support means cooperable with said first support means for maintaining said container in a given position during opening movement of said bottom, and means for actuating said bottom between its open and closed positions and being disposable in straddling relation to said maintaining means.

9. A material handling device as claimed in claim 8 wherein said bottom includes upwardly extending side members connected to said pivot means, said actuating means being adapted to engage an edge of each side member for controlling the position of said bottom.
